IMPULSE REPEATER

Willie Saville, Huyton, Liverpool, England, assignee to Associated Telephone & Telegraph Company, Chicago, Ill., a corporation of Delaware

Application June 10, 1938, Serial No. 212,885
In Great Britain July 5, 1937

3 Claims. (Cl. 179—16)

The present invention relates to telephone or like systems and is more particularly concerned with systems in which trains of controlling impulses are repeated from one exchange to another over a junction. Impulse repeating arrangements of the type in question are ordinarily incorporated in so-called discriminating selector repeater switches such as are employed in satellite exchanges and they are also provided in so-called outgoing auto-to-auto repeaters.

In such equipment two relays, generally known as relays D and I, which together form a high impedance, are bridged across the speech conductors, relay D being polarised so that supervision can be effected over the junction by reversal of current in well-known manner. During each train of repeated impulses these relays are short-circuited to improve the impulsive conditions to the distant exchange equipment, and at the end of each train they are introduced into the loop circuit of the distant impulse accepting relay. Due to their high impedance there is then a momentary drop in the loop current beyond that corresponding to their ordinary direct current resistance, and unless the impulsive relay has been energised over a very short junction so that its core is well saturated, it may release momentarily and give a false impulse to its associated switch.

In one method suggested for overcoming this trouble so that the junction impulsive limits could be extended it was arranged to decrease the initial impedance of the bridge relays by means of a second winding which was short-circuited over their normally closed armatures. This and similar schemes cannot however be easily applied to existing impulse repeating arrangements, and furthermore they require extra contacts and windings on the bridge relays. It is the object of the invention to provide a simple and cheap arrangement for overcoming the above mentioned trouble which can be readily applied to existing equipments without the necessity for appreciable modifications thereto.

According to the invention in an impulse repeater for use in telephone or like systems arranged so that an impedance bridged across the outgoing circuit is shunted during the transmission of a train of impulses, at the same time the shunt is removed a unit of non-linear resistance material connected across the impedance serves to absorb the inductive kick otherwise produced. By the term non-linear resistance material is meant material the resistance of which is substantially the same for both directions of current

flow but which decreases with increase of voltage.

The invention will be better understood from the following description of one method of carrying it into effect, reference being had to the accompanying drawing. This shows a circuit diagram of an outgoing impulse repeater AR of well-known type which is connected by way of a junction J to a final selector FS at a distant exchange. It will be understood that the diagram shows only sufficient detail to enable the invention to be properly understood.

Considering the general circuit operations, when the repeater is taken into use, relays A and B operate, and incoming trains of impulses subsequently received are repeated by the armature a_2 to the distant impulse accepting relay $1A$. Relay C holds operated during each train and at armature c_1 short-circuits relays D and I to improve the impulse repeating conditions.

At the end of each train, relay C releases after 20 its slow period and at armature c_1 removes the short-circuit from relays D and I and the unit of non-linear resistance material NLR thereby introducing them into the loop circuit including relay $1A$. The transient conditions which now obtain are difficult to describe with any degree of precision but it may be said broadly that a back E. M. F. of considerable value is generated in the highly inductive windings of relay $1A$ due to the fall of the loop current and this E. M. F. causes 30 a rapid drop to occur in the resistance of the material NLR. As the voltage applied across this material decreases so will its resistance increase but during this time the initial impedance of the bridge relays gradually falls towards the D. C. 35 resistance value. As a result the loop current is prevented from falling as far as it otherwise would do without the provision of the non-linear resistance shunt path and relay $1A$ is thereby enabled to remain operated even when long junction lines are in use. When steady conditions are reestablished, the voltage applied to the material will be small and will only be equal to the voltage drop across the D and I relays so that its resistance will be of high value and it will 40 therefore offer a negligible leakage path during any subsequent transmission of tones or speech currents over the line conductors.

In a preferred form of carrying the invention into effect, the non-linear resistance material 50 takes the form of silicon carbide mixed with carbon and/or tungsten or molybdenum which is agglomerated under pressure and subsequently baked, the resulting mass having a resistance-current characteristic which is substantially hy- 55

perbolic. The resistance material may be made into various shapes, for instance, it may be made in the form of a disc or washer and the surface metal-sprayed at appropriate points as described 5 in my United States application Ser. No. 198,182, filed March 26, 1938.

I claim:

- 10 1. In an impulse repeater, an incoming and an outgoing line, an impedance bridged across the outgoing line, a non-linear resistance connected in shunt with said impedance, means responsive to impulses received over the incoming line for transmitting impulses over the outgoing line, and means effective to short-circuit said impedance 15 only during the transmission of impulses.
- 20 2. In combination, a series circuit including a source of current, a relay, and a short-circuited impedance, said relay operated in said circuit, means for disconnecting the short circuit from said impedance, and a non-linear resistance permanently connected in shunt with said imped-

ance to prevent the relay from being restored by the disconnection of said short circuit.

3. In combination, a series circuit including a source of current, a relay, and a short-circuited impedance, said relay operated in said circuit, 5 means for disconnecting the short circuit from said impedance, a resistor permanently bridging said impedance and having a resistance value controlled by the voltage across said impedance, said resistor having, upon the disconnection of 10 said short circuit, a low resistance due to the back electromotive force generated in the impedance and effective to increase in resistance as the current flow through the impedance increases to a steady value, said resistor thereby assisting 15 in maintaining said relay operated during the transient conditions following the disconnection of said short circuit and comprising substantially an insulator when the flow of current through the impedance becomes steady. 20
